(57) **CLAIM**

The ornamental design for a display panel with transitional graphical user interface for augmented reality components, as shown and described.

DESCRIPTION

The present application is related to U.S. Pat. No. 10,528,998, issued on Jan. 7, 2020, titled, “Systems and Methods for Presenting Information, Related To Products or Services Being Shown on a Second Display Device, on a First Display Device Using Augmented Reality Technology.” The subject matter of the above identified application is incorporated by reference hereto for all purposes to the extent that such subject matter is not inconsistent herewith.

FIG. 1 is a front view of a first image in a sequence for a display panel with transitional graphical user interface for augmented reality component, according to the new design; FIG. 2 is a second image thereof; and, FIG. 3 is a third image thereof.

The broken line showing of a television screen, coffee table, and the handheld electronic device with display screen illustrate the real life, three-dimensional environment in which the design is used. The broken lines shown within the display portion of the display panel show portions of the graphical user interface. None of the broken line subject matter forms part of the claimed design.

The appearance of the transitional image sequentially transitions between the images shown in FIGS. 1-3. The process or period in which one image transitions to another image forms no part of the claimed design.

1 Claim, 3 Drawing Sheets
